(74) Attorney, Agent, or Firm — Studebaker & Brackett
PC(57) **CLAIM**

The ornamental design for a baby carrier, as shown and described.

DESCRIPTION

FIG. 1 is a front perspective view showing our new design for a baby carrier,

FIG. 2 is a front view thereof,

FIG. 3 is a rear view thereof,

FIG. 4 is a left side view thereof,

FIG. 5 is a right side view thereof,

FIG. 6 is a top view thereof; and,

FIG. 7 is a bottom view thereof.

The dotted lines in the figures represent stitching and form part of the claimed design.

1 Claim, 7 Drawing Sheets---
